UNITED STATES PATENT OFFICE.

WILLIAM P. PARSONS, OF CORNING, NEW YORK, ASSIGNOR TO CORNING GLASS WORKS, A CORPORATION OF NEW YORK.

DESIGN FOR A PERCOLATOR-TOP OF GLASS.

46,777.

Specification for Design.

Patented Dec. 15, 1914.

Application filed May 27, 1914. Serial No. 841,385. Term of patent 14 years.

To all whom it may concern:

Be it known that I, WILLIAM P. PARSONS, a citizen of the United States, residing at Corning, in the county of Steuben and State of New York, have invented a new, original, and ornamental Design for Percolator-Tops of Glass, of which the following is a specification, reference being had to the accompanying drawings, forming part thereof.

Figure 1 is a plan view of a percolator top having my design applied thereto as

the same appears to the eye. Fig. 2 is a side elevation thereof, as the same appears to the eye. Fig. 3 is a section through the percolator top of Figs. 1 and 2.

I claim:

The ornamental design for the percolator top of glass as shown.

WILLIAM P. PARSONS.
